UNITED STATES PATENT OFFICE.

RICHARD LA FRANCE, OF TOLEDO, OHIO, ASSIGNEE TO THE OWENS BOTTLE MACHINE COMPANY, OF TOLEDO, OHIO, A CORPORATION OF OHIO.

APPARATUS FOR MANIPULATING HOT GLASS.

1,390,448.

Specification of Letters Patent. Patented Sept. 13, 1921.

Application filed March 20, 1918. Serial No. 223,548.

To all whom it may concern:

Be it known that I, RICHARD LA FRANCE, a citizen of the United States, residing at Toledo, in the county of Lucas and State 5 of Ohio, have invented new and useful Improvements in Apparatus for Manipulating Hot Glass, of which the following is a specification.

My invention relates to apparatus by 10 which a continuously flowing stream of molten glass is segregated into individual gathers or masses to be introduced into forming molds.

In the co-pending application of Joseph 15 B. Graham, Serial Number 174,697, there is shown apparatus of the character above indicated, comprising a sectional cup placed directly beneath the flow opening into the bottom of a receptacle containing molten 20 glass. This cup, together with a cut-off blade forming a removable bottom for the cup, provides a temporary receptacle in which the glass accumulates to form a gob. The knife is withdrawn after a portion of 25 the charge has collected in the cup and the accumulating mass is supported by the side walls of the cup during a further accumulation of the glass. The cup sections are then separated, permitting the mass to drop into 30 a mold therebeneath, after which the cup sections come together and the knife operates to sever the charge from the oncoming stream so that the glass again accumulates to form the next charge.

35 The present invention comprises certain improvements on the apparatus disclosed in the Graham application, comprising a modified form of sectional cup, a modified operation of the knife, and an improved form of 40 knife. According to my invention, the opening in the bottom of the sectional cup is narrowed or restricted and the cup so formed that the knife after severing the glass may be withdrawn instantaneously. The glass 45 is then supported by the side walls of the cup as the gather accumulates. The knife operating mechanism is formed to effect this quick withdrawal of the knife. The primary purpose of this operation is to reduce 50 to a minimum the length of time the knife is in contact with the glass to thereby avoid chilling of the glass and thus eliminate the usual scar produced in the finished ware by such chilling.

55 Another feature of the invention relates

to the improved knife or cut-off device. In its preferred form the knife blade is a disk which slides in contact with the bottom of the divided cup. This disk is inexpensive, being a circular piece of tool steel which, 60 in case it gets dull, can readily be re-ground by an unskilled workman. It is mounted on a pivot pin which may have a slightly tapered shank permitting the disk to rock sufficiently to closely fit the under surface 65 of the cup, with the result that when the cutting of the glass takes place a close contact of the cutting edge of the disk with the corresponding cutting edge of the cup is insured. This condition also means that 70 as the cutting off has taken place the disk closes the opening in the bottom of the cup with absolutely no clearance for the glass to settle in and form a ridge or chilled corner. Shear marks are thus eliminated from 75 the finished article. The blade is free to rotate about its pivot so that any wear of the cutting edge is distributed. The cutting disk is mounted on a horizontally swinging arm and is held by spring pressure against 80 the bottom of the cup, the disk having a limited vertical movement in said arm. This arrangement avoids the necessity of any fine adjustment of the knife and permits it to automatically accommodate itself 85 to any inequalities or variations due to expansion.

Other features and advantages of the invention will appear hereinafter.

In the accompanying drawings, Figure 90 1 is a plan view of the divided cup and cut-off device, and operating means therefor.

Fig. 2 is a side elevation partly broken away of the furnace extension or booth and flowing apparatus.

Figs. 3, 4 and 5 are front sectional elevations of the same, showing the apparatus in the positions assumed at different periods in the cycle of operations. Fig. 3 illustrates a cup having a larger discharge opening 100 than in the other views and shows a portion of a gob collected in the cup. Fig. 4 shows the cup in open position with the gob dropping into a mold. Fig. 5 shows the position of parts an instant later when the cup has 105 closed and the knife operated.

Fig. 6 is a plan view of the knife and its carrying arm.

Fig. 7 is a sectional view of the same, the section being at the line 7-7 on Fig. 6.

Fig. 8 is a detail view of a cup section. The molten glass 11 may be supplied from a continuous melting tank (not shown) provided with an extension or clay boot 10. A continuous flow of glass is permitted through an opening in the bottom of the boot, said opening formed in a removable bushing 12. A metal support 13 is provided for the boot 10. Beneath the flow opening 10 is a divided cup or receptacle 14, in which the glass accumulates to form a gather or gob. This cup is made in two sections which, when the gob of glass has accumulated therein, are separated by withdrawing them horizontally to permit the gob to drop into a mold 38 therebeneath. The cup sections are then brought together again ready to receive the next charge and a knife 15 is moved horizontally across the bottom of 20 the cup to sever the discharged gob from the oncoming stream of glass.

The knife 15 may remain in position to close the bottom of the cup during the accumulation of a portion of the charge. The 25 knife is then withdrawn leaving the accumulating glass supported by the inclined side walls of the cup as shown in Fig. 3. The arrangement and operation of the cup and knife just described may be the same as 30 that disclosed in the Graham application above referred to.

The present invention, however, comprehends a modified form of cup in which the bottom opening 16 is sufficiently restricted 35 to permit the knife to be withdrawn immediately after the cutting stroke, without allowing the glass to run through said opening. With this arrangement the knife is not relied on as a temporary support for 40 the accumulating mass and by withdrawing the knife at once after the cutting stroke it does not remain in contact with the glass long enough to chill it and produce the usual scar in the finished ware.

45 The cup sections may be provided with compartments 17 in which water is circulated for cooling the cup. The flow of glass from the boot 10 is regulated by a plug 18 adjustable toward and from the flow opening.

The mechanism for actuating the divided cup 14 and knife 15 will be understood by reference to Figs. 1 and 2. The two cup sections are carried on arms 19 and 20 mounted to swing horizontally on their pivots 21 and 22. The arm 20 forms part of a bell crank lever having an arm 23 carrying a roller 24 bearing against a cam 26 on a drive shaft 27. As the cam rotates the 55 high part 36 engages the roll 24 and swings the bell crank 23, 20 to separate the cup sections 14, intermeshing gears 29 serving to transmit the motion to the arm 19. The cup is closed by springs 30 mounted on a 60 rod 31 extending freely through lugs 32 on

the arms 19 and 20. The springs are confined between said lugs and adjustable nuts 33. The knife 15 is carried by a bell crank lever 34 pivoted at 22 and having a roll 35 to bear against a cam 28 for swinging said 70 knife. The cam 28 is rotated by the shaft 27. Adjusting means 37 permits the relative position of the cams to be adjusted to thereby time the relative movements of the cup and knife. The shaft 27 is driven by or 75 in synchronism with a rotary mold table of a glass forming machine carrying the molds 38. These molds may be arranged in a circle on the mold table to be brought successively into position beneath the cup for receiving 80 the charges. The cup sections are connected to the arms 19 and 20 by pivots 39 and held at the proper angle by adjusting screws 40, which permit accurate adjustment of the abutting faces of the cup sections. Stationary supports 47 are provided for the cup sections.

The knife 15 is in the form of a disk preferably made of tool steel and having a cutting edge 50 at its circumference. The knife 90 disk is mounted on a shouldered pivot pin 51 having its shank tapered as shown at 52 (Fig. 7) to permit a slight tilting movement of the disk in any direction. The knife is yieldingly held against the bottom of the 95 cup by means of a spring 53 operating through a lever 54 pivoted at 55 to an arm 56 on which the knife is mounted. The end of the lever bears against the pin 51 which is freely slideable in the direction of its 100 length in the arm 56. A head 57 on said pin limits the movement thereof. The arm 56 is connected by a bolt 58 to the bell crank 34. The knife arm is adjusted so that the knife bears with a moderate pressure against 105 the bottom of the cup. The knife disk being free for universal tilting movement on its pivot and under spring pressure, it accommodates itself to any irregularities and bears squarely against the bottom of the 110 cup. This insures a clean cut and prevents the glass from being drawn or settling between the blade and the bottom of the cup, and thereby prevents the formation of a ridge or chilled edge which would produce 115 a shear mark in the finished ware.

Just above the mold 38 is a guide ring 60 with a flared opening in register with the mold for guiding the glass into the mold, particularly when the tail of the gob is deflected by the cutter, as shown in Fig. 5. The guide ring may also reduce the diameter of the mass of glass passing therethrough and shape it for entering the mold, as indicated in Fig. 4.

120 The operation is as follows:

Referring to Fig. 1, the drive shaft 27 is rotating continuously in the direction indicated by the arrow, carrying with it the cams for actuating the cup and knife. As the 130

- high portion 36 of the cam 26 engages the roll 24, the cup sections are separated, permitting the accumulated charge of glass to drop into the mold 38, as indicated in Fig. 4.
- 5 The cam may be so formed that the cup will immediately close after the gob has dropped therefrom, or it may be formed to hold the cup sections separated for a greater or less interval of time so that after the gob drops 10 into the mold the glass will continue to flow in a stream directly into the mold. As the cup closes or immediately thereafter, the knife is operated by the high portion 281 of the cam 28 to sever the discharged gob from 15 the oncoming stream. When the bottom opening 16 in the cup is made small enough, as shown in Fig. 8, the knife may be immediately withdrawn after its cutting stroke 20 by a spring (not shown). The accumulating glass is then supported by the inner retaining walls of the cup which are upwardly and outwardly inclined.
- When the bottom opening of the cup is made larger, as indicated in Fig. 3, the high 25 portion 281 of the knife operating cam will be lengthened to hold the knife in its forward position while a portion of the charge accumulates. The knife is then withdrawn and the glass supported by the side walls of 30 the cup until the gather is completed and the cup opened to discharge the glass.
- Variations may be resorted to without departing from the spirit or scope of my invention.
- 35 What I claim is:—
1. Means for separating a flowing stream of glass into individual masses, comprising a sectional cup in the path of the stream and in which the glass accumulates, means to 40 separate the cup sections and thereby drop the accumulated mass and then return said sections, said cup having a restricted bottom opening through which glass may flow and prevent entire disconnection of the dis- 45 charged mass from the oncoming stream, and a knife to cut the glass at said opening, said opening being of a size to prevent further flow of glass therethrough after it is cut at the opening.
  - 50 2. The combination with means to supply a stream of glass, of a receptacle in which the glass accumulates, said receptacle having a restricted discharge opening, means to momentarily enlarge said opening to discharge 55 the accumulated mass and then reduce the opening without disconnecting the dis- charged mass from the stream, a cut-off de- vice, and means to operate it to sever the stream at said opening and then to immedi- 60 ately withdraw it.
  - 65 3. The combination with means to supply a stream of glass, of a receptacle into which the glass flows, the receptacle having a dis- charge opening normally restricted to pre- vent the glass from flowing therethrough
- while accumulating in the cup, means to enlarge said opening to discharge the accumulated mass and then reduce it without stopping the flow at said opening, a knife, and means to move the knife across said opening 70 to sever the stream and immediately withdraw it, the opening being sufficiently restricted to prevent the glass from flowing therethrough after the knife has been withdrawn.
4. The combination of a tank having a flow opening, means forming a passageway through which the glass flows from said opening, means to periodically restrict the passageway at one point, and means to sever 80 the glass at said point, said restriction being sufficient to prevent a continued flow of glass therethrough after it is severed.
5. The combination with means for establishing a flowing stream of glass, of means 85 providing a passageway through which the glass flows, said passageway being restricted at one point sufficiently to permit the glass to accumulate above said restriction to form a gob, means to momentarily enlarge said 90 restriction to permit the gob to drop, a knife, and means to move the knife across said passageway at said restriction to sever the glass and to immediately withdraw the knife.
6. The combination with means for flow- 95 ing a stream of glass, of a sectional cup or receptacle in which the glass accumulates to form a gob, the inner walls of said cup being downwardly convergent and terminat- ing in a restricted opening in the bottom of 100 the cup, means to separate the cup sections and thereby drop the gob, and a cut-off de- vice to separate the gob from the oncoming stream, said opening being of a size to pre- vent a flow of the glass therethrough after 105 the cut-off has operated.
7. In apparatus for manipulating hot glass, the combination of a disk cutter, a co- 110 operating member having a flat surface against which the disk bears and a cutting edge, and means to secure automatic adjust- ment of the disk to said member.
8. In apparatus for manipulating hot glass, the combination of a disk cutter, a co- 115 operating member having a flat surface against which the disk bears and a cutting edge, and means to secure automatic adjust- ment of the disk to said member and hold the disk with a spring pressure against said member.
9. In glass cutting apparatus, the combi- 120 nation of a flat disk having a cutting edge, a coöperating element providing a flat surface over which the disk slides and having a cutting edge with which the disk coöperates to produce a shearing cut, and means to yield- 125 ingly hold the disk against said flat surface.
10. In glass cutting apparatus, the combi- nation of a flat disk having a cutting edge, a coöperating element providing a flat surface 130

over which the disk slides and having a cutting edge with which the disk coöperates to produce a shearing cut, a supporting arm in which the disk is mounted for limited movement in a direction perpendicular to its face, and a spring by which the disk is yieldingly held against said face.

11. In glass cutting apparatus, the combination of a flat disk having a cutting edge, a 10 coöperating element providing a flat surface over which the disk slides and having a cutting edge with which the disk coöperates to produce a shearing cut, said disk mounted to rotate freely about its axis and also mounted 15 for universal tilting movement, permitting the disk to accurately adjust itself to said surface.

12. A severing device for hot glass, comprising a disk, a pivot pin on which the disk 20 is mounted and free to rotate, said pin having a shank of reduced diameter extending through the disk, said shank being tapered to permit universal tilting movement of the disk thereon.

25 13. A severing device for hot glass, comprising a disk, a pivot pin on which the disk is mounted and free to rotate, said pin having a shank of reduced diameter extending through the disk, said shank being tapered 30 to permit universal tilting movement of the disk thereon, an arm in which said pin is mounted for limited movement in the direction of its length, and means to apply spring pressure to said pin in the direction of its 35 length.

14. A severing device for hot glass, comprising a disk, a pivot pin on which the disk is mounted and free to rotate, said pin having a shank of reduced diameter extending 40 through the disk, said shank being tapered to permit universal tilting movement of the disk thereon, an arm in which said pin is mounted for limited movement in the direction of its length, a lever pivoted on said arm

and having one end abutting against said 45 pin, and a spring interposed between said arm and the other end of the lever.

15. The combination with a sectional cup in which a flowing stream of glass accumulates to form a gob, of means to separate the 50 cup sections to drop the gob, a cutter arranged to bear against the bottom surface of the cup and slidably thereon to sever the gob, and means to hold the cutter with a 55 yielding pressure against the bottom of the cup.

16. The combination with a sectional cup in which a flowing stream of glass accumulates to form a gob, of means to separate the 60 cup sections to drop the gob, a cutter arranged to bear against the bottom surface of the cup and slidably thereon to sever the gob, means securing a universal automatic adjustment of the cutter to said surface, and means to hold the cutter with a yielding 65 pressure against said surface.

17. The combination with means for flowing a stream of molten glass, of means for periodically severing the stream, comprising a disk cutter and a coöperating element relatively movable transversely of the stream and operable to sever the latter by a shear cut, and means to hold said disk and coöperating element together with a yielding pressure applied in a direction transverse to 75 that of their relative movement.

18. The combination of a tank having a flow opening, means forming a passageway through which the glass flows from said opening, means to periodically restrict the 80 passageway at one point, and means to sever the glass, said restriction being sufficient to prevent a continued flow of glass therethrough after it is severed.

Signed at Toledo, in the county of Lucas 85 and State of Ohio, this 13th day of March, 1918.

RICHARD LA FRANCE.
